Patented Sept. 3, 1918.

UNITED STATES PATENT OFFICE.

ALEXANDER L. W. BEGG, OF NEW YORK, N. Y.

SYSTEM OF LOCOMOTION.

1,277,681.

Specification of Letters Patent.

Patented Sept. 3, 1918.

Application filed September 1, 1917. Serial No. 189,288.

To all whom it may concern:

Be it known that I, ALEXANDER L. W. BEGG, a citizen of the United States, and a resident of New York, in the county of New York and State of New York, have invented 5 certain new and useful Improvements in Systems of Locomotion, of which the following is a specification.

This invention relates to a system of locomotion, combining conveyers and escalators for freight and passengers. The application pertains to a form of tread having a variable speed, and in which the treads are laterally placed, such as referred to in my 15 Patent No. 1,242,641, Sept. 4, 1917; and also refers to certain details of the step formation. One of the objects of the invention is to provide an improved form of tread and step formation in which separate parts may 20 be brought together when desired and also caused to separate, and to advance at different speeds.

In the accompanying drawing showing embodiments of my invention, Figure 1 is a side elevation showing the step formations, Figs. 25 2 and 3 are details of the same. Fig. 4 shows a modification. Fig. 5 is a plan view showing the relative arrangement of the parts. Figs. 6 and 7 are side elevations of 30 the same; and Fig. 8 is a section through the ball bearing chain and tread.

I provide a series of step formations A which permit of a movement both upward and downward from the horizontal movement 35 by means of a slotted strip t firmly attached to each end of each step, and into which slides a pin i projecting from the adjoining step, whereby to permit a perpendicular relative movement when the steps 40 are caused to move up an incline, as shown in Fig. 1.

The steps A may be divided longitudinally, as shown in Figs. 2 and 3, for the purpose of causing an increase in the width, 45 and on which increase the meshing planes are brought into play; the increase in width being limited by the levers which form the link chain connecting the steps.

As shown in Fig. 5 and elsewhere, I provide lateral slats P, that compose a continuously moving platform, supported by members m that are driven continuously by a suitable motor or other driving means. Another set of lateral slats Q are arranged at 55 one side of the said slats P, and are joined by a link chain 26, running on ball bearings

j formed of balls that run between steel tubing cut laterally, or other suitable supports. The chains are driven by drums z and pinions f. The pinions engage a rack 60 g placed on the under side of the slats P and will be obviously conveyed at the same speed.

The second set of slats Q form a continuous belt on the chain 26 by which they are 65 connected, and they are caused to intrude or project between the slats P, but are taller and hence extend above the slats P, as indicated in Figs. 6 and 7; whereby they will serve to support the passengers or objects 70 that are supported by the slats P before these come together.

I also provide a deflecting means or switch by which the slats Q can be deflected laterally, as shown in Fig. 5. A sprocket wheel 75 U engages the chain 26 and a bar h causes a deflection of the chain until it reaches the sprocket wheel V, arranged laterally beyond the sprocket U as shown. This will cause the slats Q and P to separate. Beyond the 80 sprocket V are sprockets W, X and Y of increasing diameter but rotated at the same number of revolutions. This will cause the chain 26 to be compacted and bring the slats Q nearer together as shown. A similar set 85 of sprocket wheels may be provided, not shown, of progressively reduced diameters whereby the speed is again gradually increased to the normal speed.

As shown in Figs. 7 and 8 the cross members Q and also the cross members P may be supported on a special form of ball bearing device, in the form of a split tube. A similar device d is shown having its upper wall curved or cylindrical to engage substantially 95 the lower half of the balls j, as shown. The rack g has portions h on the lower face, whose bottom wall is curved as shown in Fig. 8, to engage substantially the upper half of the balls j.

Having thus described my invention, what I claim is:—

1. In a system of locomotion, a series of steps, the adjoining steps having a sliding connection permitted relatively in a vertical direction, whereby to form steps on change of movement from a horizontal path to both the ascending and the descending path.

2. In a system of locomotion, a tread divided at its center and provided with means 110 permitting extension longitudinally and meshing means arranged to unify the tread.

3. In a system of locomotion, slats arranged in two sets of unequal height, the higher of the slats projecting upwardly between the slats of the other set to form a 5 separate and active tread.

4. In a system of locomotion, slats arranged in two sets of unequal height, the higher of the slats projecting upwardly between the slats of the other set to form a 10 separate and active tread, the slats having means to deflect them obliquely sidewise.

5. In a system of locomotion, slats arranged in two sets of unequal heights, and

means by which the higher of the slats are deflected obliquely sidewise, and caused to 15 reduce the speed for a certain distance and then increase the speed to the former speed.

6. In a system of locomotion, in combination, a moving platform composed of slats the under surfaces of which form channels 20 to engage substantially the upper half of balls forming a series running in a single channel curved to engage substantially the lower half of the balls.

ALEXANDER L. W. BEGG.
